LOCKING STOP VALVE

John E. Glasscock, Oklahoma City, Okla.

Application April 13, 1937, Serial No. 136,542

1 Claim. (Cl. 292—307)

My invention relates to improvements in locking stop valves or stop cocks for use in connection with oil storage tanks.

The principal objects of my invention are to provide a device of this character which is positive in action, simple and inexpensive in construction; new, novel and easily installed; which is strong, durable, reliable and of evident utility; which cannot easily get out of order and is efficient for the purposes for which it is intended; to provide an improved dart made in two pieces, one of said pieces having a catch at its lower end, the other of said pieces being a follower to prevent the removal of the dart from the valve; to provide an enlarged head on the upper ends of said pieces having shoulders for seating against the top of the valve and alining holes for sealing the dart in any desired position and a chain for securing the said pieces against separation of one from the other.

With these and other objects in view my invention consists of the construction, novel feature and combination of parts hereinafter more fully described, illustrated in the accompanying one-sheet drawing and pointed out in the claim here-to appended. Various changes in the form, proportion, size, shape, weight and minor details of construction, within the scope of my invention may be resorted to without departing from the spirit or broad principle of my invention or sacrificing any of the advantages thereof.

In the accompanying drawing, Figure 1 is a top or plan view of a valve or stop cock showing the dart and seal; Fig. 2 is a side view of the same; Fig. 3 is a fragmentary sectional view of an oil tank showing one form of installation of stop cock and Fig. 4 is one form of the two piece dart.

The valve or stop cock on the flow line from an oil tank is installed in a pit or box as shown in Fig. 3. At present the dart is inserted from the top as in my improvement but the seal is secured at the bottom of the dart on the underside of the valve. The pit usually fills up with crude oil, mud and water and is converted into a sump. It is a very disagreeable job to reach under the valve to seal the dart and during cold stormy weather it is almost impossible to accomplish the task. With my two piece dart the sealing is done on top of the valve and it is not necessary to reach down on the under side as at present.

One embodiment of my invention is shown as follows:—The valve on stop cock 1 is of standard construction, having a spigot 2 provided with a wrench head 3 and nut 4. The barrel 5 within which spigot 2 turns has a flange 6 adjacent the head 3 of spigot 2. A rectangular opening 7 passes vertically downward through barrel 5

inside of flange 6. A corresponding rectangular opening 8 through spigot 2 is in registering alignment with the said opening 7 for holding the valve in open position. A similar opening 9 is at right angles to opening 8 through spigot 2 for holding the valve in closed position when dart 10 and follower 11 are inserted in said openings.

Dart 10 has a catch 12 at its lower end. Both dart 10 and follower 11 have heads 13 at their upper ends forming shoulders 14. Alining holes 15 pass through heads 13 and said heads are chained together with chain 16. In sealing the valve, dart 10 is inserted in openings 7 and 8 and pushed down until shoulders 14 seat on top of barrel 5. Catch 12 will protrude through hole 7 at the bottom of barrel 5 and when follower 11 is seated behind said dart 10 catch 12 will be forced over so as to engage the under side of barrel 5 and be held in locked position as can best be seen in Fig. 2. Seal 17 will be inserted through holes 15 and the valve 1 will be secured against unauthorized movement.

A typical installation is shown in Fig. 3. Valve 1 is placed in valve pit 19 under the edge of oil tank 18 on flow line 20. Dart 10, follower 11 and seal 17 are accessible from the top and it is not necessary to reach under the valve to seal and unseal the dart as at present. The rectangular openings 8 and 9 through spigot 2 being at right angles to each other, allow dart 10 and follower 11 to seat in opening 7 through barrel 5 and seal the valve in either open or closed position. In this specification, and in the figures the dart, follower and openings are described and shown as rectangular but they may be made in other forms. The openings may be drilled holes, the dart and follower each a half cylinder. I therefore do not confine my invention to the exact form shown and described but reserve the right to make changes in the shapes of the dart and openings.

Having thus described my invention what I claim as new and wish to secure by Letters Patent is:

In a device of the class described in combination with a stop cock or valve, a two piece dart consisting of a dart proper and a follower adapted to be seated in registering openings in the spigot and barrel of said valve, heads formed on said dart members having shoulders for seating on top of said barrel, said heads having alining holes for inserting a seal therethrough, a catch on the lower end of said dart member for seating under said barrel and locking in position against removal when backed up by said follower and a chain for securing said dart members against separation when not in locked position.

JOHN E. GLASSCOCK.
